ATTORNEY.

UNITED STATES PATENT OFFICE

2,228,557

FAUCET

Charles J. Camp, Palo Alto, Calif.

Application March 4, 1940, Serial No. 322,086

3 Claims. (Cl. 137—139)

This invention relates to improvements in faucets and has particular reference to a faucet which may be operated either mechanically or manually.

- 5 5 A further object of the invention is to produce a faucet which is neat in appearance, easy to manipulate even when the hands are wet, and a faucet which may be easily cleaned through the elimination of dirt collecting recesses.
- 10 10 A further object of the invention is to produce a faucet which is economical to manufacture, easy to assemble, and easy to install.

Other objects and advantages will be apparent during the course of the following description.

- 15 15 In the accompanying drawing forming a part of this specification and in which like numerals are employed to designate like parts throughout the same.

Fig. 1 is an enlarged fragmentary detailed view taken on the line I—I of Fig. 3;

20 20 Fig. 2 is an end elevation on a reduced scale and having a portion thereof broken away to show the circuit breaking contacts;

Fig. 3 is a top plan view of my faucet;

25 25 Fig. 4 is a front elevation thereof; and

Fig. 5 is a schematic diagram of the wiring.

The ordinary faucet, whether it be a combined hot and cold water faucet or a single faucet, usually includes a valve which is opened and closed through the turning of a handle or wheel. Both of these arrangements are difficult to manipulate, particularly when the hands are wet with soap suds.

I have, therefore, produced an arrangement 35 35 wherein the water in the faucet may be turned on or off through the manipulation of a drum which is manually operated or by pressing a contact so that a small electric motor will rotate the drum.

40 40 In the accompanying drawing wherein for the purpose of illustration is shown a preferred embodiment of my invention, the numeral 5 designates a casting having an undercut portion 6 in which the hinged spout 7 is located. A bore 8

45 45 extends horizontally through the casting 5 and communicates with the spout 7. In the opposite ends of this bore are formed valve seats 9, each of which is adapted to be engaged by a reciprocating valve as shown at 11. This valve 50 50 is provided with a thread 12, which thread threadedly engages an internal thread formed in the hub 13 of the drum 14, which drum is mounted in a recess 16 formed in the end of the casting and having its upper portion extending

55 55 above the top of the casting, as illustrated in

Figs. 1 and 2 and shown at A. This drum rotates upon the stub end 17 of a threaded plug 18, threaded in the opening 20. This plug also carries a flat pin 19 which enters a flat channel formed in the valve 11. A packing gland is 5 5 shown at 21, the purpose of which is obvious.

The drum 14 is provided with an internal gear 22, which gear is engaged by the pinion 23 connected to the motor shaft of a motor 24. This motor is of the reversible type and its direction of rotation is controlled by a pair of contacts 26 and 27 which are in turn engaged by rocking a contact 28. These contacts are all enclosed in a rubber casing 29 so as to be protected against moisture and likewise to protect 10 10 the user against shock. Mounted within the drum 14 is a contact pin 31 which is adapted to hit either the spring 32 or 33, which springs are so connected to the circuit that when they are contacted, the circuit will be broken and the motor stopped.

In assembling my faucet and assuming that the bore and the valve seats have been formed, the drum 14 is placed in the recess 16 and moved to its proper position. The valve is then passed through the opening 20 so that its threads engage the internal threads in the hub of the drum. The plug 18 is now screwed into the opening 20 and the flat pin 19 positioned in the plug and secured in place as by the plug 25. 25 30 35

The motor assembly, which is carried by plates 30, (see Fig. 3) is secured to the top of the casting in any desired manner. The springs 32 and 33 extend into the drum so as to be in alignment with the pin 31. 35

When the device is so assembled, it will be apparent that by moving the contact 28 so that the contact 26 is engaged, the motor will rotate in one direction, rotating the drum until the pin engages either of the contact springs 32 or 33, and the motor will be stopped. This will result in the opening or closing of the valve, depending upon the rotation of the motor. It is obvious that should it be desired to rotate the valve a slight distance, the same can be accomplished by merely holding the contact 26 or 27 closed for a brief interval. It is also apparent that if I desire to manually control the valve, I may do so by rotating the drum manually, it, of course, being understood that the drum will be roughened so as to provide a suitable purchase thereon. 40 45 50

It is to be understood that the form of my invention herewith shown and described is to be taken as a preferred example of the same and 55

that various changes relative to the material, size, shape and arrangement of parts may be resorted to without departing from the spirit of the invention or the scope of the subjoined 5 claims.

Having thus described my invention, I claim:

1. In a faucet of the character described, a casting, an undercut portion formed on the outer surface of said casting, a spout positioned 10 in said undercut portion, a bore formed in said casting and connected to said spout, the bore having a valve seat formed therein, a valve movable in said bore and adapted to engage said seat, a drum rotatable on said valve and having 15 threaded engagement therewith, said drum being positioned in said casting and having a portion thereof extending above the top of said casting, and means for preventing said valve from rotating, whereby the actuation of said drum 20 will reciprocate said valve.

2. In a faucet of the character described, a casting, an undercut portion formed on the outer surface of said casting, a spout positioned in said undercut portion, a bore formed in said casting 25 and connected to said spout, the bore having a valve seat formed therein, a valve movable in said bore and adapted to engage said seat, a drum rotatable on said valve and having threaded engagement therewith, said drum being positioned

in said casting and having a portion thereof extending above the top of said casting, means for preventing said valve from rotating, whereby the actuation of said drum will reciprocate said valve, and a threaded plug and a stub portion 5 on which said drum rotates and carrying said last-mentioned means.

3. In a faucet of the character described, a casting, an undercut portion formed on the outer surface of said casting, a spout positioned in said undercut portion, a bore formed in said casting and connected to said spout, the bore having a valve seat formed therein, a valve movable in said bore and adapted to engage said seat, a drum rotatable on said valve and having 15 threaded engagement therewith, said drum being positioned in said casting and having a portion thereof extending above the top of said casting, means for preventing said valve from rotating, whereby the actuation of said drum 20 will reciprocate said valve, a threaded plug and a stub portion on which said drum rotates and carrying said last-mentioned means, and a reversible motor positioned in said casting and having geared connection with said drum, whereby said drum may be rotated when said motor is energized.

CHARLES J. CAMP.
